OF POTTER HEIGHAM, ENGLAND.

LOOM.

Application filed February 25, 1925, Serial No. 11,430, and in Great Britain February 27, 1924.

This invention relates to the weaving art, and has for its principal object the direct production in a loom, of fabrics or articles of wearing apparel of varying width or length in different parts thereof, thereby enabling said articles to accommodate themselves or conform to the shape of the body.

A further object of the invention is the provision, in combination with a loom, of efficient means for selectively taking up sections of the warp threads independently of other sections during the weaving operations, so as to produce a fabric the length or width of which varies in accordance with a predetermined design.

With the foregoing and other objects in view, which will appear as the description proceeds, the invention consists in the novel features of construction and combination of parts which will be more fully described hereinafter and particularly pointed out in the claims.

In the drawings accompanying and forming part of this specification,—

Fig. 1 (which is on Sheets 1 and 2) is a general elevation in the nature of a diagram showing in part the improvements applied to an ordinary type of loom provided with jacquard or other harness shown diagrammatically only in Figs. 1 and 7 the creel being indicated in side elevation.

Figs. 2 and 3 are views in enlarged side elevation and plan of one of the controlled units (that is the rearmost one) supplying each a warp end from a separate head on the creel and these views are to be examined with respect to the creel shown in Fig. 1.

Fig. 4 is a rear end elevation of one half of the creel seen in Fig. 1.

Fig. 4a is a detail view of parts also shown in Fig. 4.

Fig. 5 shows a diagrammatic plan view of the two halves of the creel the latter being illustrated in the drawings as made in two parts, one being movable to the left and the other to the right to easily open up access to the reed through which the warps pass and to allow of access to supply fresh sources of warp ends on the inside of the halves of the creel.

Fig. 6 is a diagram indicating one form of mechanism which may be used to actuate

the parts controlling the sectional feed of the selected sections of warp.

Fig. 7 is a side view showing one group of the sectional feed mechanism and the means for actuating the same.

Fig. 8 shows a rear elevation of certain of the parts seen in Fig. 7.

Fig. 9 is a partial plan view of Fig. 7.

Fig. 10 shows separately the sectional feed mechanism.

Fig. 11 is a detail plan view of Fig. 10.

The drawings show a wooden built-up creel marked generally A, the creel illustrated being in two parts as indicated in Fig. 5 each properly supported and flexibly secured by thin flexible springs A' to the loose reed baulk. Each package carrier of warp, as for instance the cheeses a, is carried upon a spindle a' fixed in the horizontal bars a², one spindle a' serving for two cheeses a or package carriers one on either side of the horizontal bars a². A movable bent wire a³ keeps the cheeses in place on the spindle (see Fig. 3) such bent wire a³ being capable of swivelling out of place to allow of ready introduction of the cheeses a. Each warp end a^x drawn off the cheese a passes under and then over a fixed tensioning rod a⁴ and is then led under the bent wire a³ of the next package carrier group immediately in the rear and a weight a⁵ puts a tension or load on each warp end a^x.

The warp ends a^x from each horizontal bar a² are led over a grooved wooden sleeve a⁵ carried upon a spindle a⁶ also fixed in the horizontal bar a². A bent wire a⁷ confines each grooved wooden sleeve a⁵ in place, one wire a⁷ serving two grooved wooden sleeves a⁵ as is obvious from Fig. 3, which represents the rearmost group in connection with a package carrier on each horizontal bar a².

Each package carrier may be otherwise controlled and loaded by any known or suitable means calculated to permit of compact grouping of the supply for each warp end and to resist too easy rotation of each warp end.

It is clear that in the illustrated arrangement six properly tensioned warp ends a^x from each side of each horizontal bar a² pass over each grooved sleeve a⁵ and these warp ends a^x are led downwards and upwards

according to whether the disposition of source of supply is above or below the horizontal level of the line of the "shed."

We show the warps coming downwards and upwards as passing between the teeth of combs *b*, *b* two in connection with each complete unit of the creel. The said warps then pass around rollers *c*, *c* carried on spindles *c'*, *c'*. The intention is to keep each warp end separate and distinct and to bring the warp ends in regular order into a horizontal plane and this is illustrated by Fig. 1.

The warp threads *a* all lying in a horizontal plane are next passed through the dents of a loose reed *d* which is an easy fit in the slot of two supporting baulks *d'*, *d'*, carried on the flexible springs *A'*.

The warp ends are next passed through healds *e* which are actuated by "jacquard," "dobby" or any other harness capable of providing considerable shedding power. In the drawing the warp ends are supposed to be threaded through the assembly of healds *e* which are operated according to the cards or other pattern controlling arrangement governing the shedding as well known.

The warp ends next pass through the beat-up reed *f'* and over the sley *f* which works and beats-up in ordinary manner and the shuttle is reciprocated in the shed in known fashion. If varied weft is to be inserted the loom may have movable shuttle box mechanism.

From the sley *f* the woven fabric or garment passes through a temple *g* of suitable type. The temple roller *g* is sustained in slidable slotted brackets *g'* braced by wires *g''*, the brackets being capable of yielding against springs *g'''*. The fabric next passes to sectional rolls to be dealt with later, and over a breast-beam *h* to ordinary batching mechanism, not shown.

Prior to reaching the breast-beam *h* and batching mechanism the fabric is acted upon by sectional rolls. These may be arranged at right-angles to the direction of travel of the warps across or partly across the width of the loom, or same may be arranged at an angle or diagonally and these means are in effect the sectional taking-up devices.

We illustrate a series of closely spaced upper and lower rolls of narrow width say $\frac{3}{8}$ " or more or less and such rolls work in pairs (one upper and one lower) or sets as may be requisite. The series of rolls may have any desired disposition viewed in plan as explained, as for example they may be parallel one to another, or they may incline slightly on opposite sides of the centre, or a varied disposition may be arranged.

In the drawing we illustrate upper rolls *i* which are each carried upon a shaft *i'* in a bent metal frame *i''* fulcrumed at *i'''*. A spring *i''''* held from the longitudinal angle-

iron cross-bar *j* presses on each bent-metal frame so as to provide a resilient pressure on the sectional upper roll *i*, which roll may be covered with rubber or such roller may be spiked or serrated or of other type. The lower roller *k* is shown toothed or serrated and is rotatable upon a shaft *k'*, and gearing with this lower roller *k* is a toothed pinion *l* carried on a shaft *l'*. With this toothed pinion *l* gears a small pinion *m* on a shaft *m'* and which small pinion *m* is compounded with a ratchet wheel *n*. The ratchet wheel *n* is acted upon at the required times to effect the sectional feed. The centres supporting the wheels *k*, *l*, *m*, and *n* are carried in closely pitched brackets *n'*. The arrangement illustrated for acting on the ratchet wheel *n* consists of a lever *o* fulcrumed at *o'* and which has a spring held pawl *o''* pivoted at *o''* the upper end of the lever *o* having a preparation or contacting face *o'''*. Thus we provide a series of actuating levers with pawls, one lever for each pair of sectional rolls, such levers being closely pitched and arranged like pedals or keys located side by side across the width of the loom. By acting on the ratchet wheel *n* any pair of sectional feed rolls *i*, *k* may be actuated to effect a feed. When not acted upon any such pair of rolls will cease to feed.

Whenever a lever *o* is actuated it operates its pair of feed rolls *i*, *k* as stated, and, if not actuated the rolls *i*, *k* are not operated and no feed takes place across that section, weft not being inserted in such section and no sectional take-up occurring.

Each lever *o* fulcrumed at *o'* is flexibly connected by a cord or attachment *o''* to a provided heald and tie-up to the jacquard or the like, or to one of the healds and tie-ups in each separate section to be separately controlled, the object being to effect a sectional taking-up as and when required. For example, if 25 warp ends pass between two sectional take-up rolls then only upon actuation of the heald controlling that section will a feed of warp take place.

With respect to the drawings: if the controlling tie-up *o''* for any section be actuated by the jacquard, or equivalent means, then the lever *o* is moved on its fulcrum *o'* and the pawl *o''* is carried down and slips over the teeth of the ratchet wheel *n* and sets ready for the sectional feed to be effected.

Below the preparation or contacting face *o'''* on each individual lever *o* is arranged a rockable cam *p* carried on a spindle or shaft *p'* operated by a lever *p''* which lever is connected by a link *p'''* to a cranked lever *p''''* fulcrumed at *p'''''*. This cranked lever *p''''* is operated by a revolving cam *q* on the shaft *q'* driven in any suitable manner from any revolving part of the loom.

The result of this arrangement is, that the cam p is always being rocked and whenever the jacquard acting through the particular flexible connection or connections c sets one or any of the levers o by raising the longer end, then on the next upward rocking motion of the cam p one or more of the sectional feed rolls are operated through the ratchet mechanism. In effect, the jacquard mechanism selects and sets the levers o which are to operate to actuate the desired sectional rolls and it will be understood that unless the harness actuates any particular lever the cam p does not influence such lever.

Although we have mentioned jacquard controlled harness for actuating the levers o we do not restrict ourselves to such because other suitable controlling mechanism may be employed as will be understood. The ordinary healds are tied-up in ordinary fashion and each heald has or may have a cord or "lingoe" or weight as indicated. The shed controlling healds pass up through a cumber-board such as r of ordinary or suitable description.

The creel A illustrated, is, as stated, made in two parts each capable of being moved one to the right and the other to the left to a slight extent. This gives easy access to the central part of the back of the loom and allows of ready replacement after exhaustion of the warp supplies upon the spindles in the creel.

The structure carrying the sectional feed rollers and gear for each set of feed rolls i , k is shown as consisting of brackets s with shaped timber longitudinal member t to which the thin metal bracket supports n' for the sectional rolls are secured, the brackets s being braced by the angle-iron bar j , the complete structure being adjustably bolted to the back of the breast beam h by bolts h' , provision being made in the form of oppositely arranged slots or otherwise to permit of adjustment.

It will be clear that the harness, of whatever type, sets the pedal levers o and controls same and whenever one or more is set the actuation follows on the upward rocking motion of cam p and the related sectional feed takes place only over the selected section or sections of warp.

Whatever the particular arrangement of means for actuating any set or sets of sectional rolls, the sectional taking-up devices are independent and harness controlled and sufficiently narrow to affect only the desired width of warp space, and thus, just as the harness controls so a sectional taking-up is effected. We thus, in equivalent manner control the take-up over narrow sections and we control any sections by harness mechanism, and we provide means to actuate the sections which the harness allows to be actuated.

The fabric or garments woven in our loom is or batched upon a beam in any suitable fashion or otherwise taken up when finished by means appropriate for the purpose.

We have indicated how a sectional take-up of the warps can be brought about for the time being across such stretches or widths where it is desired that the relative length shall be longer, and it is obvious that shorter stretches or widths stand still or move more slowly as the character of the garments or fabric requires.

In the weaving of garments or fabrics according to our invention it is apparent that the warps are moved in sections of any number of unit warps and the movements of the sections can vary to any desired extent or relatively while the weft is inserted to such an extent as to suit and conform with the sections of warp which are for the time being advanced, and require to be filled with weft; or according to the shuttling facilities provided in the loom. The whole arrangement lends itself to sectional control of the warps longitudinally and to sectional control of the weft laterally and with respect to the entire width.

As an instance of the character of garments to which our invention is applicable we may refer to a corset. It is to be understood however, that our invention includes the direct production in the loom of other garments or fabrics from which garments can be fashioned, and to other fabrics or length which might with advantage be woven to desired form in our new loom.

If a built-up corset be examined it is obvious that the garment gradually enlarges above the waist line and is shaped to accommodate and fit the breasts, and, that such corset is also enlarged or made more accommodating where it fits around the hips below the waist line. This shaping of the garment has hitherto been done by building it up of a number of sections stitched together, with strengthening and shape preserving parts, as is well known.

By means of the present invention a garment or a fabric can be woven direct to conform to a required shape to fit or partly fit the figure or desired part of the body.

Obviously our invention is susceptible of considerable modification and amplification and the foregoing is intended only to indicate its nature and with respect to a loom of the simplest character.

We declare that what we claim is:

1. The combination with a loom having a harness, of a series of independent pairs of rotatable feed rollers extending across the loom, independent gearing for rotating each pair of rollers, normally inoperative ratchet mechanism adapted to engage said gearing, means automatically actuated by the harness

for selectively setting said ratchet mechanism in operative relation to said gearing; and a rocking cam member adapted to actuate the set ratchets thereby to rotate the 5 gearing associated therewith.

2. The combination in a loom, of a harness, a creel with horizontal bobbins arranged in tiers, mechanism for guiding the warp threads from above and below to pass horizontally to the reed, a series of independent 10 pairs of closely pitched feed rollers extend-

ing across the loom, means for rendering said feed rollers normally inoperative, independent gearing for rotating each pair of rollers, and ratchet means operated by a cam and with provision for selection of the sectional means of feeding by actuation from the harness all for the purposes related. 15

In testimony whereof they have signed their names to this specification.

STEPHEN BARNWELL.

REGINALD HARRINGTON BARNWELL.
